(57) CLAIM

The ornamental design for compact garment packaging, as shown and described.

DESCRIPTION

FIG. 1 is a top, front, left side perspective view of the compact garment packaging of the invention;

FIG. 2 is a top plan view thereof;

FIG. 3 is a right side view thereof;

FIG. 4 is a rear view thereof;

FIG. 5 is a bottom plan view thereof; and,

FIG. 6 is an exploded view thereof.

The broken line showing of environment is for illustrative purposes only and forms no part of the claimed design.
